UNITED STATES PATENT OFFICE

SAMUEL J. SIEGEL, OF NEW YORK, N. Y., ASSIGNOR TO CARTHAGE MILLS INCORPORATED, OF CARTHAGE, CINCINNATI, OHIO, A CORPORATION OF OHIO

DESIGN FOR A RUG

Application filed January 17, 1929. Serial No. 29,650. Term of patent 7 years.

To all whom it may concern:

Be it known that I, SAMUEL J. SIEGEL, a citizen of the United States, residing at New York, in the county of New York and State of New York, have invented a new, original, and ornamental Design for Rugs, of which the following is a specification, reference being had to the accompanying drawing, forming part thereof.

In the drawing:

The figure is a top view of the rug, showing my new design.

I claim:

The ornamental design for a rug substantially as shown.

SAMUEL J. SIEGEL.
